UNITED STATES PATENT OFFICE.

LUTHER C. MEYERS, OF BRIDGETON, NEW JERSEY.

PRESS.

Application filed September 27, 1922. Serial No. 590,839.

To all whom it may concern:

Be it known that I, LUTHER C. MEYERS, residing at Bridgeton, New Jersey, a citizen of the United States, have invented certain new and useful Improvements in Presses, of which the following is a specification.

My invention relates to presses, such as cutting and punching presses of the open-throat type wherein the frame extends upward and forward from the base and overhangs the latter. As ordinarily made press frames for this type of press have been made of a one piece casting and when as often happens, they are broken by accident, or 15 overload, the entire frame is ruined and must be replaced and at considerable loss because the whole frame is quite expensive. The object of my invention is to diminish the danger of breakage from overload and 20 to avoid the loss of the entire frame should breakage occur, and my invention consists in connecting the base and head members by tie rods which will take the tensile stresses which have to be borne by the frame of the 25 type of presses in question and neutralize, or obviate the shearing stresses that tend to cause the frame parts sliding on one another.

In the accompanying drawings:

Fig. 1 is a side elevation of a cutting press 30 frame embodying my invention;

Fig. 2 is a front elevation thereof;

Fig. 3 is a view partly in plan and partly in section in a plane extending horizontally above the base of the press;

Fig. 4 is a side elevation of an embodiment 35 of my invention in which the tie rods of a pair are made in one piece.

In making my present invention I have had particularly in view a construction 40 which while as efficient as that shown in my Patent No. 1,280,106 issued September 24, 1918, will be more economical to make and in some respects possess other advantages.

Referring to the cutting press frame 45 shown in Figs. 1 and 2, it will be seen that it is composed of a base member, 10, having a plane or flat top, a head member which is composed of two similar elements, 11, which have half boxes, 12, to furnish bearings for the shaft which extends from side to side of the press, and a body member, 13, which, at its lower end rests upon the base at the rear thereof, the two being secured together, and at its upper end at each side has secured 50 to it the two elements forming the head member, 11, the abutting faces of the va-

rious members being plane, or flat. The body member, 13, inclines upward and forward so that as will be seen from Fig. 1 of the drawings the ram reciprocating shaft 60 overhangs the work on the bed of the press. At each side of the press and extending continuously from the bottom of the base, 10, upward through an opening in the body, 13, and the head elements, 11, and emerging on 65 the top of the latter, is a tie device of double crossed rods, 15, that is intermediate the fulcrum, or bearing point upon which the body member, under load, tends to rock upon the base, 10, and the line of thrust between 70 the shaft supported by the head elements, 11, and the base, so that the tie rods are practically in the line of greatest tensile strains and, hence, take the tensile stress which the frame must bear. Each tie rod, 75 15, of a pair is continuous and straight from end to end and emerges below the base, 10, and above the head, 11, the emerging portion being screw threaded to receive a nut, 16, and each rod of a pair extends at the incline at the same angle from top to bottom, 80 which in the case of one rod is upward and forward to bring its upper end closer to the point of upward thrust exerted on the head, 11, and in the case of the other rod is upward and rearward, the two rods crossing substantially at the plane of the flat top of the base, 10, the two rods of a pair passing alongside one another so that they lie in parallel vertical planes. As the forwardly 85 inclined rod of a pair under tensile stress tends to straighten up or shift backward under the pull upon it, it causes a tendency of the head 11, to shift rearwardly, but the other rod by its rearward inclination opposes that tendency and hence horizontal shear by any sliding tendency of the head is eliminated. As a pair of tie rods at each side of the press consists of two simple 90 straight rods, the construction is obviously an inexpensive one. Moreover each rod of a pair being straight from end to end the tensile stresses are transmitted in a straight line from end to end of the rod. This last-named advantage may be secured by making the two rods of a pair in one piece as 95 shown in Fig. 4, the two rods, 150, being in effect joined where they intersect, and the straight extremity of each rod of the joined pair terminating in a threaded portion to 100 receive the anchoring or securing nut. 105

As a result of the forward position of the

lower portion of the upwardly and rearwardly inclined rod or member which has the effect of shortening the lever arm towards the vertical center line of the ram, 5 there is less strain on the base and the rods, for a given ram pressure, as compared, say, with a rod dropped vertically from the plane of the top of the base at the point where the inclined rod enters the base.

10. What I claim is:

1. A press frame for open throated presses comprising base, head and body members made of separate pieces, and a pair of tie rods, at either side of the press extending through and joining said pieces, said tie rods being situated in rear of the line of thrust between head and base members and forward of the fulcrum point upon which said connected members tend to rock and each tie rod extending in a straight line from the base to head members, each of such rods at both extremities being separate from the other and each having at such point member engaging securing means.

2. A press frame for open throated presses comprising base, head and body members made of separate pieces, and a pair of tie rods, at either side of the press extending

through and joining said pieces, said tie rods being situated in rear of the line of thrust 30 between head and base members and forward of the fulcrum point upon which said connected members tend to rock and each tie rod extending in a straight line from the base to head members, and each having 35 member engaging securing means, each tie rod of a pair being separate from the other and the two lying in parallel planes.

3. A press frame for open throated presses comprising base, head and body members made of separate pieces, and a pair of tie rods, one at either side of the press, extending through and joining said pieces, said tie rods being situated in rear of the line of thrust between head and base members and 40 forward of the fulcrum point upon which said connected members tend to rock and each extending at an incline throughout its length, one being inclined upward and forward and the other upward and rearward 45 and the two intersecting at or substantially at the plane of the top of the base member.

In testimony whereof I hereunto affix my signature.

LUTHER C. MEYERS.
